UNITED STATES PATENT OFFICE.

WILLIAM S. SAWYER, OF SPOTSWOOD, NEW JERSEY.

FOOT-WARMER FOR ATTACHMENT TO RADIATORS.

No. 806,482.

Specification of Letters Patent.

Patented Dec. 5, 1905.

Application filed February 24, 1905. Serial No. 247,168.

To all whom it may concern:

Be it known that I, WILLIAM S. SAWYER, a citizen of the United States, residing at Spotswood, in the county of Middlesex and State of New Jersey, have invented a new and useful Foot-Warmer for Attachment to Radiators, of which the following is a specification.

This invention relates to foot-warmers, and has for its object to provide a simply-constructed device of this character adapted for detachable coupling to a radiator and having means for receiving a portion of the heating medium from the same and wherein the heating medium is caused to freely circulate.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of embodiment of the invention capable of carrying the same into practical operation.

In the drawings thus employed, Figure 1 is a plan view, and Fig. 2 is a sectional elevation, of one of the improved devices, together with a portion of a radiator to which it is attached.

Fig. 3 is a transverse section of the improved device, showing a modified form of the construction.

The improved device comprises a closed drum 10, preferably of sheet metal and disposed in an inclined position and increasing in area toward the upper end and provided with spaced ears 11 12, extending from the larger end for embracing a certain number of the columns 13 of a radiator and secured in position thereon by the tie-rods 14. The drum is also provided with an interior diaphragm 15, extending from side to side of the same and spaced from the upper and lower ends, the plate serving as a "baffle" or circulating plate to insure the proper circulation of the heating medium within the drum. The upper and lower faces of the drum will preferably be curved, as shown, and the baffle-plate 15 likewise curved to correspond.

When applied to a radiator having steam as a heating medium, a steam-supply pipe 16 will be tapped into the radiator-supply 17 and connecting into the drum, as at 18, the supply-pipe 16 having a shut-off valve 19 to con-

trol the supply, the drum having a small valve 20 to dispose of the water of condensation. If hot air is the heating medium employed, the lower side of the drum will be perforated, as at 23 in Fig. 3, to admit the air to be heated. The drum may thus be arranged to receive the heating medium direct from the radiator, as in Figs. 1 and 2, or by radiation only, as in Fig. 3.

The drum is provided with a suitable support 24 to maintain it at the required distance from the floor, (represented at 26.)

It will thus be noted that a very efficient and conveniently-arranged foot-warming device is produced, which may be inexpensively manufactured, easily installed, and adapted to all the various forms of radiators in common use.

The construction of the drum 10 with the upper and lower walls inclined upwardly and diverging toward the upper end and with the baffle-plate extending from side to side within the same and spaced from the ends of the same is an important feature of the invention, as the interior of the drum constantly enlarging toward the upper end accelerates the circulation by providing a constantly-increasing area for the rising medium.

Having thus described the invention, what is claimed is—

1. A heating-drum formed with upper and lower walls inclined upwardly and diverging toward the upper end, a baffle-plate within said drum and extending from side to side thereof and spaced from the ends of the same, and means for supplying the heating medium to said drum at the lower end.

2. A heating-drum formed with upper and lower walls inclined upwardly and diverging toward the upper end, a baffle-plate within said drum and extending from side to side thereof and spaced from the ends of the same, said drum having spaced wings at the ends for bearing upon the sides of radiator members, tie-rods connecting said wings, and means for supplying the heating medium to said drum at the lower end.

In testimony that I claim the foregoing as my own I have hereto affixed my signature in the presence of two witnesses.

WILLIAM S. SAWYER.
